(57) **CLAIM**

The ornamental design for a support bracket, substantially, as shown and described.

DESCRIPTION

FIG. 1 is a plan view of the present support bracket, in a first embodiment;

FIG. 2 is a bottom elevational view thereof, the top elevational view thereof being substantially a mirror image;

FIG. 3 is a side elevational view thereof, the opposite side elevational view being substantially a mirror image;

FIG. 4 is a plan view of the present support bracket, in a second embodiment;

FIG. 5 is a bottom elevational view thereof, the top elevational view thereof being substantially a mirror image; and,

FIG. 6 is a side elevational view thereof, the opposite side elevational view being substantially a mirror image.
